(57) **CLAIM**

The ornamental design for an electrically heated towel rack, as shown and described.

DESCRIPTION

FIG. 1 is a perspective view of an electrically heated towel rack of showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings depict portions of the electrically heated towel rack that form no part of the claimed design.
